UNITED STATES PATENT OFFICE

135,063

DESIGN FOR A SAVINGS BANK

John J. Misley, Yonkers, N. Y., assignor to Baron & Arnof, Inc., New York, N. Y., a corporation of New York

Application April 24, 1942, Serial No. 106,684

Term of patent 3½ years

To all whom it may concern:

Be it known that I, John J. Misley, a citizen of the United States, residing at Yonkers, in the county of Westchester and State of New York, have invented a new, original, and ornamental Design for a Savings Bank, of which the following is a specification, reference being had to the accompanying drawing forming part thereof.

The figure is a perspective view of a savings bank, showing my new design.

I claim:

The ornamental design for a savings bank, as shown.

JOHN J. MISLEY.
